poration, New York, N. Y., a corporation of
Maryland

Application January 21, 1936, Serial No. 60,031
In Great Britain January 26, 1935

4 Claims. (Cl. 209—170)

This invention relates to improvements in apparatus for concentrating minerals by flotation.

In the carrying out of flotation processes, it has been customary to employ apparatus having 5 a porous medium through which air is delivered under pressure into the ore pulp so that the air-bubbles, rising through the pulp, carry with them particles of valuable mineral and form a froth on the pulp surface which can be collected. 10 In such apparatus, it is customary to either fix the porous medium in the bottom of the cell, or else movably mount it on a carrier in the midst of the pulp body, but regardless of whichever arrangement may be employed, the porous medium is liable to become chocked with sediment or "blinded" over a portion of its area, thus rendering it incapable of effectively serving to distribute air through the whole body of pulp. In order to recondition the apparatus for use, the porous medium must be either cleaned or renewed, thus necessitating a complete shut-down 15 of the apparatus to permit the cleaning or renewal operation to be carried out.

Important objects of the present invention are 20 to decrease the likelihood of the porous medium becoming clogged and to facilitate its being cleaned or renewed without necessitating a shut-down in the operation of the apparatus.

Other objects and advantages of the invention 25 will become apparent from the following description, taken in connection with the accompanying drawings, in which—

Figure 1 is a vertical longitudinal section through the apparatus;

Figure 2 is an end view in the plane 2—2 of 30 Figure 1 looking in the direction of the arrows;

Figure 3 is a view in the same plane but looking in the opposite direction, namely in the direction of the arrows 3—3 and showing only the 35 face of the distributing valve;

Figure 4 is a detail of air cells taken in section upon the line 4—4 of Figure 1;

Figure 5 is a detail of the porous medium in section to an enlarged scale, and

Figure 6 is a side elevation of the discharge 40 end of a modified form of apparatus.

Referring to Figures 1 and 2, a framework 11 supports flanged idlers 12, 13 which carry a horizontal cylindrical pulp vessel 14 having outer walls 15 and end flanges 16, 17. The end flange 16 carries a concentric and conical end plate 18 having a flared mouth 19, the minimum internal diameter of which, as shown at 20, determines the maximum liquid level within the pulp vessel 14.

The end flange 17 has bolted to it an end plate 53

21 to which is secured, concentrically with the axis of the pulp vessel, a valve plate 22. Disposed around the interior of the pulp vessel 14 there are a number of triangular tubular air cells 23 which, as shown in Figure 4, are disposed with 5 one apex 24 of the triangle abutting upon the outer wall 15 of the pulp vessel and with a flat base portion 25 of the triangular air cell facing towards the interior of the pulp vessel. The bases 25 abut upon one another, corner to corner, and 10 they contain perforations 26 over which is stretched a porous fabric 27. The air cells are held in situation by means of bolts 28 and they are connected at one end, by means of pipes 29 which pass through the end plate 21, with the 15 valve element 22.

It will be seen that the porous material 27 is, in effect, stretched all around the interior of the pulp chamber. The porous material consists of rubber sheeting which has been pierced with double conical holes 30, as shown in Figure 5. Between the cells or pipes 23 a water-tight joint is made by rubber tubing 47 similar to the material known as draught tubing.

The valve element 22 rotates with the pulp 25 chamber and each of the pipes 29 opens into a port 31 in the end face of the valve element 22. An air distributing plate 32 is held concentric with the valve element 22 and is pressed against it by springs 33 which are backed up by 30 a bracket 34 carried on the framework 11. The distributing plate contains an air port 35 which is connected to an air line 36 and the dimensions of the air port 35 are such as to ensure that the ports 31 in the rotating valve element are connected to the air pressure supply during the time in which the air cells to which they are coupled lie beneath the pulp level in the pulp vessel 14.

It will be observed that in the centre of the valve element 22 there is secured, concentric with 40 the pulp vessel 14, a driving shaft 37 and this is connected to reducing gear 38, 39 and thence by other reduction trains (not shown in the drawings) to the power supply.

Pulp outlets 40 pass through the end wall 21 45 of the pulp vessel, said outlets being disposed upon the largest radius which lies within the internal surface in the porous medium 27. The pulp outlets are connected to delivery pipes 41 which serve to drain tailings from the apparatus 50 into a launder 42. The pulp outlet pipes 41 drain out pulp from the pulp chamber only at such time as that in which they lie beneath the liquid level in the chamber and therefore they do not require to be provided with any controlling valves. 55

- The pipes 41 are made readily removable so that several sets of pipes of differing sizes may be provided which are readily interchangeable with one another, the size of pipe employed being chosen to suit the volume of pulp being treated. Minor variations in rate of pulp flow are taken care of automatically because if the pulp level rises in the pulp vessel 14 the number of tailings discharge pipes 41 which are active, increases.
- 10 The pulp in the pipe 43 enters the pulp vessel 14 through the open discharge mouth 19 and delivers pulp to the interior of the chamber below the pulp level and nearer to the mouth 19 than to the plate 21.
- 15 In the operation of this apparatus ore pulp which is to be subjected to flotation is delivered through the pipe 43 to the interior of the pulp vessel 14 until it reaches a level such as that indicated by the line 44 in the drawings, this line 20 lying somewhat below the level of the bottom 20 of the mouth 19. Air is admitted through the air line 36 to the cells 23, and the valve 22, 32 controls the delivery so that only those cells which lie below the pulp level receive any air. The air 25 issuing beneath the pulp level through the apertures 30 (Figure 5) aerates the pulp and produces a froth which overflows through the mouth 19, while tailings escape through the discharge pipes 41, when these lie beneath the pulp level, into 30 the launder 42.

The modification illustrated in Figure 6 shows an air distributing plate 50 held in position by means of a spiral spring 51 around the shaft 37, and bearing on the distributing plate 32. The latter is carried on a roller bearing inside the plate which bearing is carried on the shaft 37. The plate 50 is prevented from rotating by any convenient locking device such as the arm 52 which extends down to an adjusting screw 53 by 40 which the plate may be advanced or retarded. With this construction the cylinder could be rotated not by the shaft 37 but by means of chain and sprockets operating on one of the shafts of the idlers 13 or by direct attachment to the pulp 45 vessel 14 thus eliminating the train of gears. In this way the main vessel would "float" on the idlers and alignment is simplified, as well as which wear on the idlers does not affect the alignment of the air distributing valve. Moreover 50 this construction makes it easy to mount the pulp vessel on an inclined axis and to vary the inclination if this is found desirable.

Any necessary reagents can be introduced into the pulp before delivering it to the flotation vessel 55 14 or a special reagent delivery pipe can be added if desired to carry the reagents into the pulp in the interior of the vessel.

The movement of the porous medium during the flotation operation is advantageous because it 60 tends to prevent any collection of sediment of heavier or coarser particles at any one place on the porous bottom. Moreover, any coarser particles which may settle and are valuable will be carried up the side of the flotation vessel as far 65 as the froth level where they are launched on the froth by gravity, and it is a feature of the apparatus herein described that coarser, that is to say less finely ground pulp can be efficiently floated.

70 Moreover, in the event of it being necessary to run the plant for a portion only of a day the machine can be left with a load of material in it and efficiently started up on the resumption of work because the movement of the flotation vessel will distribute the ore again into the liquid.

In the event of it becoming necessary to repair or replace any section of the porous medium the flotation vessel can be stopped in its rotation with the particular porous unit which requires attention above the pulp level, and this unit can then be removed and replaced rapidly. Moreover, the distributor valve can be so designed, if desired, that air can be applied to selected units while they are above the froth level with the object of blowing the porous medium clear of any obstructions in the pores and this can be done, if desired, under the control of the operator without stopping the machine. Even while the rotation of the flotation vessel is interrupted for renewal or replacement of a unit, flotation can still 10 go on uninterrupted.

15 Although a particular tubular construction of porous medium has been hereinbefore described by way of example it will be understood that other constructions may be adopted and that 20 the porous medium may be constituted if desired by a continuous band of material passing beneath the pulp. It is one advantage of the present invention that the whole of the horizontal area beneath the pulp is covered by the porous 25 medium and can be effectively aerated thus leading to a maximum capacity for a given size of machine.

If necessary a spiral projection may be arranged 30 inside the discharge mouth 19 of the apparatus, or a spiral conveyor can be mounted inside the pulp vessel, to propel the froth outwardly. Instead of feeding the ore pulp in at the same end of the apparatus as the froth discharge it may be fed in through the opposite end, if desired.

35 If desired valves may be provided to control the tailings outlets as well as the air inlets. A valve for this purpose might be made, similar to the valve for the air inlets but on an increased scale, or alternatively a non-return valve in each 40 tailings outlet could be provided which would close automatically when the outlet came above the pulp level and would thus prevent any tendency of tailings to drip back out of the outlets into the pulp within the vessel.

45 I claim:

1. A flotation apparatus comprising a flotation vessel mounted for rotation about a given axis and having a froth-discharge opening at one end thereof and including a porous wall-like structure adapted to support an ore pulp for treatment, a plurality of air cells grouped about and movable with said wall-like structure and communicating with said vessel by way of individual portions of that structure, valve means operating 50 incident to rotation of said vessel for opening and closing successive air cells to a source of air supply, and tailings-discharge means communicating with said vessel and operable to relieve that vessel of tailings at a point well below the pulp 55 level.

2. A flotation apparatus comprising a flotation vessel mounted for rotation about a given axis and having a froth-discharge opening at one end thereof and including a porous wall-like structure adapted to support an ore pulp for treatment, a plurality of air cells grouped about and movable with said wall-like structure and communicating with said vessel by way of individual portions of that structure, valve means operating 60 incident to rotation of said vessel for opening and closing successive air cells to a source of air supply, and tailings-discharge means communicating with said vessel and operable to relieve that vessel of tailings at a point well below the pulp 65 70 75

level, said tailings-discharge means being characterized by a series of outlets grouped about said axis of rotation and communicating with said vessel at points in proximity to said wall-like structure and successively operable incident to rotation of said vessel.

3. A flotation apparatus comprising a flotation vessel mounted for rotation about a given axis and including a pair of end walls one of which is provided with a froth-discharge opening and further including a plurality of porous elements grouped about said axis and collectively forming a porous wall-like structure adapted to support an ore pulp for treatment, a plurality of air cells grouped about and movable with said wall-like structure and communicating with said vessel by way of said porous elements, each of said cells including one of said porous elements, means for removably supporting each of the said cells and 20 its included porous elements in an operative position intermediate said end walls, valve means operating incident to rotation of said vessel for opening and closing successive air cells to a source of air supply, and tailings-discharge means communicating with said vessel and operable to relieve that vessel of tailings at a point well below the pulp level.

4. A flotation apparatus comprising a flotation vessel mounted for rotation about a given axis and including a pair of end walls one of which is provided with a froth-discharge opening and further including a plurality of porous elements 5 grouped about said axis and collectively forming a porous wall-like structure adapted to support an ore pulp for treatment, a plurality of air cells grouped about and movable with said wall-like structure and communicating with said vessel 10 by way of said porous elements, each of said cells including one of said porous elements, means for removably supporting each of said cells and its included porous elements in an operative position 15 intermediate said end walls, valve means operating incident to rotation of said vessel for opening and closing successive air cells to a source of air supply, and tailings-discharge means communicating with said vessel and operable to relieve that vessel of tailings at a point well below the 20 pulp level, said tailings-discharge means being characterized by a series of outlets grouped about said axis of rotation and communicating with said vessel at points in proximity to said wall-like structure and successively operable incident 25 to rotation of said vessel.

STANLEY TUCKER.
